No. 872,740.

PATENTED DEC. 3, 1907.

A. MCKENZIE.
METALLIC CASE OR CASKET.
APPLICATION FILED DEC. 27, 1906.

UNITED STATES PATENT OFFICE.

ANGUS MCKENZIE, OF CANTON, OHIO, ASSIGNOR OF ONE-HALF TO W. W. STEPHENS, OF CANTON, OHIO.

METALLIC CASE OR CASKET.

No. 872,740.

Specification of Letters Patent.

Patented Dec. 3, 1907.

Application filed December 27, 1906. Serial No. 349,806.

To all whom it may concern:

Be it known that I, ANGUS MCKENZIE, a subject of the King of Great Britain, residing at Canton, in the county of Stark and State 5 of Ohio, have invented certain new and useful Improvements in Metallic Cases or Caskets, of which the following is a specification.

My invention relates to improvements in metallic cases or caskets, referring particularly to a box or case of the "knock down" character; the object of the invention being the provision of a simple and substantial construction of box, the parts of which may be shipped in a separated or folded condition so 15 as to occupy but a small space, and which may readily and quickly be assembled and set up for use by even an unskilled person and without the use of any tools of any sort.

Another object of my invention is the provision of a metallic case having close-fitting joints which may be sealed with cement or other like sealing substance to render the case completely air-proof, so as to protect the contents of the case against decay or injury 20 from the elements, and to thus provide a practical and inexpensive box or case which is adaptable for a great variety of uses.

With these and other objects in view, my invention consists of a case comprising separable sections, the sections having interlocking joints with each other, and clamps for adjustably securing the sections together, and the invention further comprises certain other novel features of construction, and 25 combination of parts substantially as herein disclosed.

Figure 1, is a perspective view of a case constructed in accordance with and embodying my invention. Fig. 2, is a transverse sectional view thereof, to show the manner in which the top, sides and bottom are secured together. Fig. 3, is a cross sectional view of one of the corners of the case, the view being taken on line 3—3 of Fig. 1. Fig. 4, is a broken sectional view of a modified form of connection for the top and sides of the box, and Fig. 5, is a similar view of another slightly modified form of the same, and, 45 Fig. 6 is a sectional view of another form of the same.

My improved box or casing is made of metal, preferably sheet steel, which may be readily stamped or rolled into the desired form, and in the accompanying drawings;

the numeral 1, indicates the top of a box 55 embodying my invention, the said top or cover having the downwardly turned outer flange 2, formed on its edges.

The numeral 3, designates one of the sides of the box which is formed with a plain upper 60 edge, and the lower edge is doubled over or bent back upon itself to provide a groove or recess 4, and the extreme edge is thence directed outwardly at an angle to provide the retaining or securing flange 5, as clearly 65 illustrated in Fig. 2. The top, sides and ends may be formed with the raised or embossed panels 6, if desired, this feature being a mere matter of taste. The bottom 7, of the box is formed with the downwardly 70 struck annular flange 8, adapted to be engaged in the groove or trough 4, in the lower edge of the side, the groove being of the proper size to form a close joint. A turn button 9, is pivoted at 10, on the outer face 75 of the bottom and the forward end of the button is adapted to engage the retaining flange on the extreme edge of the side member, and as many of these turn buttons are provided as are necessary to securely lock 80 the sides and bottom together, the ends being formed and secured in the same manner as are the sides.

The corners of the sides and ends are connected by means of the angular corner posts 85 11, having the inturned edges 12, adapted to engage and interlock with outwardly turned edges 13, on the ends of the side and end sections. To render the joints between the members air tight, a cement filling 14, 90 or other sealing substance may be poured in the joints, as shown in the sectional views.

In order to provide for a close joint and seal between the sides and the top of the box, I employ a connecting member 15, as shown 95 in Fig. 2. This member has an annular recess 16, formed therein which engages and fits over the upper edge of the sides, and is further provided with a trough or U-shaped annular channel 17, in which is engaged a 100 gasket 18, of rubber or similar elastic material. The cover is thus brought in contact with the rubber or other gasket used and the flange on the outer edge of the cover, makes close connection with the outer wall 105 of the connecting member. Clamping hooks 19, are pivoted in lugs or ears 20, carried on the sides and ends of the box, and the ex-

tremities of the hooks project inwardly over the edge of the cover, clamping screws 21, being mounted in the extremities of the hooks to clamp the cover against the gasket.

- 5 In Fig. 4, the connecting member is formed with an annular channel 22, fitting over the edge of the side, and the inner portion of the member is doubled back upon itself as at 23, and extended straight upward so as to be 10 engaged by the edge of the cover. In the modification shown in Fig. 5, this connecting member or strip, is simply doubled back upon itself to provide the trough 24 for the reception of the edge of the side section, and 15 the outer edge of the strip is directed laterally to form a supporting flange 25, upon which the cover rests and is supported.

From the foregoing description taken in connection with the drawings, it will be 20 evident that I have produced a separable box which accomplishes all the results set forth as the objects of my invention, and which is generally useful wherever a hermetically sealed box or case is desired.

- 25 In the modification illustrated in Fig. 6, the intermediate or connecting strip is of S-shaped formation in cross section to provide the oppositely-disposed troughs or grooves 26 and 27, which are adapted to re-

ceive the side of the box and the depending 20 edge of the cover respectively.

I claim:

1. A sheet metal casket comprising a bottom having downturned annular edges, sides and ends having their lower edges doubled 35 back to provide a groove-way to receive the flanged edges of the bottom, thence directed laterally to form a securing flange, turn buttons pivoted to the bottom and engaging the lateral securing flange. 40

2. A sheet metal casket comprising a bottom having downturned edges, sides and end sections having lower edges doubled back to provide a groove-way to receive the flanged edges of the bottom and further provided with an angularly directed securing flange to abut against the bottom, turn buttons pivoted to the bottom to clamp against said securing flange, and means for securing the abutting ends of the side and end sections. 45 5

In testimony whereof I affix my signature in presence of two witnesses.

ANGUS MCKENZIE.

Witnesses:

ATTEL POMERENE,
J. L. ROBB.
